ELECTRIC SWITCH

Benjamin Putterman, Brooklyn, N. Y., and Daniel E. Reed, Norwalk, Conn., assignors to Yankee Metal Products Corp., Norwalk, Conn., a corporation of New York

Application February 3, 1939, Serial No. 254,390

9 Claims. (Cl. 177—311)

This invention relates to improvements in switch units. It is particularly applicable to switch units adapted to be used for controlling directional signals on automobiles and other vehicles.

Many proposals have heretofore been made relative to the construction of switch units for controlling circuits to directional signals associated with automobiles. In a large number of instances these switch units are adapted to be secured to the steering post of the vehicle. Because these switch units are located in a position where they are in full view of persons in a vehicle and may be inadvertently touched by persons getting into or out of a vehicle, it is highly desirable that they have casings which not only present a pleasing appearance but which also shield the electrical connections of the switch.

Many of such prior switch units include a switch in which the manual control member is in the form of an arcuately swinging lever, which lever protects through and is movable arcuately in a slot provided in an end wall of the casing.

It is an object of the present invention to provide a switch unit of the same general character as the switch units mentioned above, but which may be more easily and economically produced than prior known units and which are especially pleasing in appearance and sturdy in construction.

In the prior switch unit involving a switch with an arcuately swingable control lever member extending through a slot in the end wall of the casing, there is normally a very real problem in the insertion of the switch in the casing in such a way that the control member is readily insertable in the slot. If the slot is made wide enough to permit a ready insertion of the control lever, the casing becomes unsightly and the electrical connections not well shielded, whereas if the slot is made more narrow the control lever often fouls the end wall when it is attempted to insert it in the slot.

An important object of the invention, therefore, is to provide a switch unit which may be very easily assembled.

A feature resulting from the attainment of the above object resides in the provision of a switch unit in which a base member is provided which may be readily inserted in the bottom of the casing and which locates an axially rotatable contact moving member relative to an aperture in the top wall of the casing.

Another and related feature of the invention resides in the provision of a control member ex-

terior the casing, which has a portion adapted to close the aperture formed in the casing for the rotatable contact moving member of the switch.

Another feature of the invention resides in the provision of a switch unit in which a single means, readily insertable in the casing, is provided for supporting and properly locating both a main switch and a pilot lamp relative to apertures in a wall of the casing.

Another feature of the invention resides in the provision of switch unit in which a novel base member not only supports a main switch and a pilot lamp in a casing but also divides the casing into two chambers and provides a partial closure for the casing bottom.

Other objects and features will hereinafter appear.

In the drawings:

Figure 1 is a top view of a switch unit embodying the invention, a portion of the control member being removed.

Fig. 2 is a view taken on the line 2—2 of Fig. 1.

Fig. 3 is an exploded side view of the switch unit.

Fig. 4 is an exploded perspective view of the main switch and the base member.

Fig. 5 is a detail view of the control member.

Fig. 6 is a wiring diagram of the switch unit.

Before describing the present improvements and mode of operation thereof in detail it should be understood that the invention is not limited to the details of construction and arrangement of parts shown in the accompanying drawings, which are merely illustrative of the present preferred embodiments, since the invention is capable of other embodiments, and the phraseology employed is for the purpose of description and not of limitation.

Referring more particularly to the drawings, there is shown a switch unit 11 including a main casing 12 having a top wall 13, side walls 14 and 15, end walls 16 and 17 and an open bottom 18, in which is confined a main switch 19, and a pilot lamp 20 comprising a socket member 21 adapted to receive a suitable electric light bulb 22.

As shown, the switch unit 11 is especially adapted to be associated with the steering post, not shown, of an automobile and, to this end, a standard 23 is provided which is connected at one end to the end wall 16 of the main casing 12 and at the other end to a bracket 24 which may be clamped to the steering post in any suitable manner. Preferably the standard is of

tubular construction for receiving a plurality of conductors 25, 26 and 27, which may be encased in a suitable cable 28, inserted in an opening 29 in one of the end walls 30 of the bracket, and 5 passing through the tubular standard into the main casing 12.

Of importance, there is provided a novel base member 31 through the use of which the final assembly of the switch unit is greatly facilitated. 10 This base member 31 may be advantageously formed by bending a piece of sheet metal, and includes laterally offset sections 32 and 33 joined by a transverse section 34. Interned portions 35 are provided on one of the offset sections 33 to constitute ears by which the base member may be fixed to the main casing. In the other offset section 32 a slot 36 is provided, extending from one end thereof toward the transverse section, and adapted to aid in properly locating the main 15 switch 19.

As shown, the main switch 19 includes a contact housing 37 in which a spring pressed movable contact member 38 is provided for movement to open and close a plurality of different 20 circuits 39 and 40, as for example to a right signal light 41 and a left signal light 42, by selectively bridging fixed contacts 43, 44 and 45, see Fig. 6, and associated binding posts 46, 47 and 48.

Also, the main switch 19 includes an axially 25 rotatable contact moving member 50 which through an eccentric 51 is connected at one end to the movable contact member 38 and extends forwardly through a detent plate 52 spaced from and connected to the contact housing 37 by a 30 tubular section 53. Fixed on the end of the contact moving member 50 extending through the detent plate is a member 54 carrying a pair of cup-shaped retainers 55 and 56 adapted to locate spring pressed detents 57 which snap into depressions 58 and 59 defined by projections 60 and 61 stamped in the detent plate. As clearly shown 35 the closed ends of the retainers project forwardly from the member away from the detent plate.

The novel base member 31 provided by the present 40 invention is especially advantageous in the mounting of a switch such as the main switch 19 above described. Thus, it is merely necessary to fit the tubular connecting section 53 in the slot 36, and the projections 60 and 61 on the detent 45 plate serve to cooperate with the sides of the slot to properly locate the main switch 19 relative to the offset section 32. Suitable fastening elements such as screws 62 may be utilized to fix the detent plate of the main switch to the base member, 50 with the contact housing extending rearwardly in the direction of the transverse section and with the rotatable contact moving member 50 and associated detent plate positioned forwardly of the 55 offset section 32.

In addition to serving as a mounting for the main switch 19 the base member 31 is also adapted 60 to serve as a mounting for the pilot lamp 20, and associated relay 63 including an electromagnet 64 for controlling a circuit 65 through the pilot lamp. Thus, as shown most clearly in Figs. 2, 3, and 6, the socket member 21 of the lamp is fixed to the offset section 33 to extend forwardly therefrom, being separated therefrom by a suitable insulating plate 66. The electromagnet 64 is shown as mounted on a finger 67 extending 65 forwardly from a metal contact plate 68 interposed between the insulating plate 66 and the offset section 33. And, the magnet controlled movable contact 69 is mounted on a spring arm 70 electrically connected to the contact plate 68.

The fixed contact 71 of the relay 63 is provided by a finger 72 on a metal strip 73 separated from the contact plate 68 by the insulating plate 66 and connected to the socket member 21 of the pilot lamp.

As shown most clearly in the wiring diagram in Fig. 6, the lead conductor 25 may be conveniently associated with a binding post on an ammeter of the automobile and secured to a binding post 75 on the switch unit, which is connected by one wire 76 to the electromagnet and by another wire 77 to the pilot lamp. Another wire 78 connects the electromagnet with the center binding post 46 of the main switch. Conductors 26 and 27 extend into the main casing 12, then through an aperture 79 in the transverse section 34 of the base member and are respectively connected to the right and left binding posts 47 and 48 of the main switch. As shown these conductors 26 and 27 may lead to the right 20 and left signal lights 41 and 42. A wire 77 connects the binding post 75 with the pilot lamp. And, as shown, the circuit 65 of the pilot lamp may be completed by grounding the metal strip 73 through the main casing in a manner now well understood.

In the operation of the switch unit, when the main switch is operated to close either of the circuits 39 or 40 current is caused to flow in a predetermined amount if the circuit is in good order and the relay 63 is operated in a well known manner to close the circuit to the pilot lamp. If either of the circuits 39 or 40 is not in good order, for example if the right or left signal light has burned out, the relay will not operate to close the circuit to the pilot lamp.

While prior electric switch units of the same general nature as the one forming the subject matter of the present invention have been in use for some time, these prior switch units have in the main presented very real problems in assembly. If oversized casings were used the assembly was somewhat simplified, but in the case of units designed for mounting on automobile steering posts the demand was and is for units which are compact and pleasing to the eye.

With the switch unit provided by the present invention, assembly of the several main parts is a relatively simple matter. Thus, the main switch 19 and the pilot lamp and relay may be mounted on the base member outside of the casing, and the base member then inserted in the open bottom 18 thereof and fixed thereto by screws 80 passing through the side walls of the casing and into the ears on the offset section.

When thus inserted in the casing, the base member locates the socket member 21 of the pilot lamp so that it extends toward and through an aperture 81 in the top wall of the casing. A washer 82 serves to insulate the socket member from the top wall of the casing. As shown, the projecting end 83 of the socket member is threaded to receive an insulating translucent threaded cap 84 which closes the aperture 81 and permits light from the pilot lamp to be seen exterior of the casing.

Also, the base member locates the axially rotatable contact moving member 50 of the main switch relative to an aperture 85 in the top wall of the casing. This aperture 85 is shown as being of circular shape and somewhat larger than the pilot lamp aperture 81, and adapted to receive a forwardly extending flange 86 on the detent plate.

Of importance a novel control member 87 is provided for controlling the main switch exterior

the casing. This control member includes an up-standing lever section 88 and a portion 89, preferably circular in shape, adapted to close the aperture 85, and recessed to provide a chamber 90 for receiving the flange 86 on the detent plate and also the member 54 and associated projecting ends of the detent retainers 55 and 56. Preferably, and as shown, stop shoulders 91 are provided on the flange 86 for engaging the retainer carrying member 54 and thus arresting movement of the contact member 38 in circuit closing positions. The detents 55 and 56 engage in the depressions 58 and 59 to arrest the contact member 38 in a central circuit opening position.

To facilitate a proper locating of the control member relative to the axially rotatable contact moving member 50, a rib 92 is provided on the inside of the recessed portion, shaped to define a socket 93 or slot for receiving and closely confining the forwardly projecting ends of the retainers 55 and 56. Thus, in effect, a key and slot means is provided not only for properly locating the control member 87 and contact moving member 50 relative to each other, but also for arresting relative rotative movement between the members. Screws 94 passing through the control member and into a fastening plate 95 on the contact moving member 50 may advantageously be utilized for maintaining the key and slot means in operative relation and for fixing the control member 87 relative to the contact moving member 50 within the casing.

It is to be particularly noted that in the switch unit provided by the present invention the control member is associated with the main switch exterior of the casing and after the switch has been fully mounted. There is thus eliminated the assembly problem present in many prior units, of inserting the main control lever through a slot in the end of the casing during the insertion and mounting of the switch.

In the completely assembled switch unit it is to be particularly noted that there are no unsightly openings in the top, sides or ends of the casing where dirt might easily enter. Also, it is to be noted that the transverse section 34 of the base member divides the casing into two chambers 96 and 97 for the main switch 19 and relay 63 respectively, and that the offset section of the base member serves as a partial closure for the casing bottom. The pilot lamp and relay chamber 97 is thus substantially enclosed so that no glare from the pilot lamp will unduly light up the interior of the car and so that the relay mechanism is most effectively shielded.

In addition, and as shown, when a shoulder 98 is provided on the socket member 21 to limit movement thereof through the aperture 81, it is to be noted, see Fig. 2, that the threaded cap 84 serves not only to provide a light transmitting closure for the aperture 81 but also to lock the socket member 21 and through the latter the base member 31 relative to the main casing. In connection with the fixing of the socket member 21 to the offset section 33 particular attention is directed to the reduced hollow portion 99 of the socket member which extends from a shoulder through the offset section 33 to receive the wire 77. A washer 100 insulates the reduced portion 99 from the base member and a peened over flange 101 cooperates with the shoulder to fix the socket member to the base member.

Variations and modifications may be made within the scope of this invention and portions of the improvements may be used without others.

Having thus described the invention, what is claimed as new is:

1. An electric switch unit comprising a main casing having a wall with an aperture therein; a base member having a slot therein with an open end; means for fixing said base member relative to said casing with the slot opposite said aperture; an electric switch in said casing, supported by said base member and having an axially rotatable contact moving member extending through said slot and toward said aperture; a separate control member exterior said casing and connected to said contact moving member; key and slot means associated with said control member and said rotatable member for locating said members relative to each other and for arresting relative rotation therebetween; and means for maintaining said key and slot means in operative relation.

2. In a switch unit the combination of a main casing having a wall with an aperture therein; a base member having a slot therein; means for fixing said base member relative to said casing with the slot opposite said aperture; an electric switch in said casing, supported by said base member and having an axially rotatable contact moving member extending through said slot and toward said aperture; and a separate control member, exterior said casing, having a portion closing said aperture and connected to said rotatable member.

3. In a switch unit the combination of a main casing having a wall with a pair of spaced apertures therein; a main electric switch for controlling a main electric circuit, having an axially rotatable contact moving member extending toward one of said apertures; a relay and pilot lamp electrically associated with said main switch; a base member having laterally offset sections and an intermediate transversely extending section, said intermediate section dividing the casing into a main switch chamber and a relay chamber, one of said offset sections supporting said switch and the other of said offset sections locating said pilot light relative to the other of said apertures; and a separate control member, exterior of said casing and connected to said contact moving member.

4. In a switch unit the combination of a main casing having a top wall, side walls and an initially open bottom, said top wall having an aperture therein; a base member, secured to said casing, having laterally offset sections and an intermediate transversely extending section, said latter section extending towards the front wall, one of said offset sections having a slot with an open end and being located adjacent said front wall and aperture, and the other of said offset sections serving as a partial closure for said bottom; an electric switch in said casing and supported by said base member, having an axially rotatable contact moving member extending through said slot and towards said aperture; and a control member, exterior said casing, having a portion connected to said rotatable member.

5. In a switch unit including an electric switch having an electric contact portion, a detent means spaced from the contact portion, a connecting section between the contact portion and the detent means, and an axially rotatable contact moving member extending from said contact portion and associated with the detent means; the combination of a main casing having a wall with an aperture therein; a base member secured to said casing, having a slot with an open end for receiving said connecting section,

for supporting said switch in said casing with the rotatable member extending toward said aperture; and a separate control member, exterior said casing, having a portion aligned with said aperture and connected to said rotatable member.

6. A switch unit comprising a main casing having a top wall, side walls and an initially open bottom, said top wall having a pair of spaced apertures therein; a main electric switch for controlling a main electric circuit, having an axially rotatable contact moving member; a pilot lamp electrically associated with said main switch; a base member insertable in said open bottom, supporting said main electric switch and said pilot lamp with said rotatable member extending in the direction of one of said apertures and with said pilot lamp extending in the direction of the other of said apertures; a section on said base member extending toward said top wall intermediate said apertures and dividing the casing into separate chambers for said main switch and said pilot lamp; and a separate control member, exterior said top wall and connected to said rotatable member.

7. A switch unit comprising a main casing having a top wall with a pair of spaced apertures therein, side walls and an open bottom; a main electric switch having an axially rotatable contact moving member; a pilot lamp electrically associated with said main switch; a base member insertable in said open bottom; laterally offset sections on said base member, respectively supporting and locating said rotatable member and said pilot lamp relative to said apertures, said pilot lamp supporting and locating section providing a partial closure for said open bottom; and a separate control member, exterior said top wall, having a portion connected to said rotatable member and closing the aperture associated with the latter.

8. In a switch unit including an electric switch having an electric contact portion, a detent plate spaced from the contact portion, a connecting section between said plate and said contact portion, an axially rotatable contact moving member extending from said contact portion through said detent plate, means on said rotatable member and overlying said detent plate, a pair of raised portions on said last named means, and detents associated with said raised portions; the combination of a main casing having a wall with an aperture therein; a base member insertable in said casing, having a slot with an open end for receiving said connecting section, for supporting and locating said switch with the rotatable member extending in the direction of said aperture; and a control member, exterior said casing, having a portion for receiving and closely confining said raised portions to thereby locate said control member relative to said rotatable member and arrest relative rotatable movement therebetween.

9. In an electric switch unit the combination of a main casing having a wall with an aperture therein; a base member for supporting a main electric switch; a pilot lamp having a socket member with a threaded end extending through said aperture, electrically associated with said switch and fixed to said base member; means on said socket member for limiting movement of said threaded end through said aperture; a threaded light transmitting cap, screwed on said threaded end for closing said aperture and cooperating with said means to lock said socket member and base member relative to said casing; and a control member for controlling said switch exterior said casing.

BENJAMIN PUTTERMAN,
DANIEL E. REED.
